UNITED STATES PATENT OFFICE.

HENRY BEZER, OF NEW ROCHELLE, NEW YORK.

RAILWAY SIGNALING SYSTEM AND APPARATUS.

SPECIFICATION forming part of Letters Patent No. 602,792, dated April 19, 1898.

Application filed December 3, 1895. Renewed February 25, 1898. Serial No. 671,692. (No model.)

To all whom it may concern:

Be it known that I, HENRY BEZER, a subject of the Queen of Great Britain, and a resident of New Rochelle, in the county of Westchester, State of New York, have invented certain new and useful Improvements in Railway Signaling Systems and Apparatus, of which the following is a specification, reference being had to the accompanying drawings, forming part hereof.

My invention relates to railway signaling systems and apparatus, and has for its objects generally to provide an improved visual indicator for giving indications of the condition of the track in advance of a train, and to provide for moving the signal by positive rotative movements, and for the employment of a single visual indicator as both a home and distant signal, and to provide means for positively locking the indicator in one or more predetermined positions, and for controlling the motor by the locking device both for starting and stopping the signal, and to provide two batteries, either one of which may be the main battery and the other a reserve battery, and means for reversing the conditions of these batteries when the active battery becomes too feeble to perform its work, thus guarding against battery failure and insuring the successive use of the batteries.

Other objects and advantages of my invention and the various improvements constituting my invention are hereinafter fully set forth and claimed.

The drawings illustrate embodiments of my invention.

Figure 1 is a front elevation of a signal embodying my invention. Fig. 1^a is a detail plan view of the lantern. Fig. 2 is an enlarged plan view of the signal with the cover of the signal-box removed to show the actuating mechanism and with parts of the mechanism broken away. Fig. 3 is an enlarged front elevation of the mechanism with the box and signal-shaft in section. Fig. 4 is a vertical section taken on the line 4-4 of Fig. 2. Fig. 5 is a diagrammatic view illustrating the circuits and part of the apparatus adapted for automatically actuating the signal when rail-circuits are employed. Fig. 6 is a diagrammatic view illustrating the circuits and part of the apparatus adapted for automati-

cally actuating the signal when track instruments are employed. Fig. 7 is a diagrammatic view showing the main and reserve 55 battery and means for throwing the reserve battery into action. Fig. 8 is a similar view showing a different construction for accomplishing the same purpose.

The visual indicator is shown as consisting 60 of a substantially straight semaphore-blade B⁷ for the day signal and a lantern L for the night signal.

The semaphore-blade B⁷ is medially pivoted and fitted to rotate, being suitably secured 65 upon the front end of a shaft B⁸, and the axis of rotation of the semaphore-blade is located at a distance from the post or support P, so that the post or support forms no part of the background of the semaphore in any position 70 that the semaphore-blade may assume. As a result of this construction I secure a landscape background for the semaphore-blade in all positions and may employ the horizontal and vertical positions, as well as the oblique 75 position, of the semaphore-blade to give positive indications to the train-engineer.

By reason of the number of positions which may be utilized I am enabled to employ one straight semaphore-blade both as a home and 80 distant signal, and in the construction shown the horizontal position of the semaphore-blade B⁷ (shown in full lines in Fig. 1) is the home danger-signal, indicating that the block or section of track in advance of the signal 85 is occupied by a train, and the oblique position of the semaphore-blade (shown in dotted lines in Fig. 1) is the distant danger or caution signal, indicating that the block or section of track in advance of the signal is clear, 90 but that the second block or section of track in advance is occupied by a train, and the vertical position of the semaphore-blade (also shown in dotted lines in Fig. 1) is the safety-signal, indicating that a plurality of blocks 95 or sections of track, in this case two blocks or sections of track, is clear of trains. The indications thus given are simple and essentially distinct, so that confusion or misinterpretation of the signals should not occur.

The lantern L is fitted to rotate upon a vertical axis and to move with the semaphore, so that when the semaphore gives the home danger-signal the face L' of the lantern is exhib-

itted to the train-engineer, and this face L' may have a red lens or bull's-eye, and when the semaphore gives the distant danger-signal the face L^2 is exposed, and this face may have a green lens or bull's-eye, and when the semaphore gives the safety-signal the face L^3 (see Fig. 1^a) is exposed, and this face may have a clear or amber bull's-eye lens, showing a white or amber light. Thus the lantern L will give night signals corresponding to the day signals given by the semaphore-blade. The connection of the semaphore and lantern is shown as effected through intermeshing bevel-gears B^4 and L^4 , the bevel-gear B^4 being secured upon the semaphore-shaft B^3 and the bevel-gear L^4 being secured upon a shaft L^5 , extending upward through a protecting-housing L^6 , and the shaft L^5 having secured or formed upon its upper end a block or holder L^7 , adapted to enter a suitable socket of the lantern L, and to enter that socket only when the lantern is turned in the proper position to give an indication corresponding to that of the semaphore-blade. The semaphore-shaft B^3 and lantern-shaft L^5 are shown as geared together in the ratio of one to two, so that the lantern makes one complete revolution for every half-revolution of the semaphore-shaft, for the reason that the semaphore, being medially pivoted and symmetrical or composed of two diametrically opposite arms of the same shape, gives the same indications in diametrically opposite positions, and will therefore move through any one indicating position twice in every revolution—as, for instance, from the home danger position (shown in full lines in Fig. 1) a half-revolution of the semaphore will bring it into diametrically opposite position; but this position will be apparently the same by reason of the symmetrical shape of the semaphore.

The actuating mechanism of the signal is shown as incased within the box N, having a cover N', to which cover is secured the housing L^6 , above referred to, of the lantern-shaft L^5 . The signal-box N may be cast in one piece and is shown as provided with perforated bosses N^2 N^3 for the reception of bolts to hold it to an arm P', extending horizontally from the post P, and this arm may be bolted to the post, as shown, and should be narrower than the semaphore-blade, and may be quite narrow, so as to be scarcely visible to the train-engineer, or visible only as a thin line. This arm P' is the only connection between the signal and its post or support. It is of course evident that where two signals are desired, as in a four-track system, the other signal may be similarly supported on the opposite side of the post, and where the signal has a horizontal support, as a bridge, the supporting-arm P' may extend vertically from the horizontal support to the signal-box N. The semaphore-shaft B^3 is shown as fitted to rotate in bearing pieces or blocks held in the box N, the front bearing-piece B^5 being

open at both ends, as the shaft emerges from the box at this bearing to hold the semaphore, and the rear bearing-piece B^6 being externally closed, so that the shaft is not exposed to the weather at its rear end. These bearing-pieces may be made of a suitable non-rusting metal or alloy or composition, so as to guard against rusting of the shaft in its bearing, and good results have been obtained with a steel shaft and brass bearings.

The motor M is not shown in detail, as any suitable motor may be employed; but the motor-shaft M' is shown as extending therefrom. I propose to use an electromotor, and have shown in the diagram Figs. 5 and 6 the circuit connections for actuating said motor. These connections will be hereinafter particularly described. The motor-shaft M' is shown as provided with a pinion M², meshing into a gear-wheel M³, said gear-wheel M³ being secured upon a shaft M⁴, fitted to rotate in externally-closed bearings held in the box N. A second pinion M⁵ is also secured upon the shaft M⁴ and meshes into a gear-wheel M⁶, secured upon the semaphore-shaft B³, and thus the rapid rotation of the motor-shaft M' produces a slow rotation of the semaphore-shaft B³ and the motor has a very considerable leverage upon the semaphore-shaft, so as to readily overcome any resistance to the movement of the semaphore.

In the operation of the system herein shown and described the semaphore rotates always in the same direction and moves through only a part of a revolution at a time—as, for instance, from the horizontal position to the vertical position one-fourth of a revolution, or from the vertical position to the horizontal position one-fourth of a revolution, or from the horizontal position to the oblique position one-eighth of a revolution, or from the oblique position to the vertical position one-eighth of a revolution, or from the oblique position to the horizontal position three-eighths of a revolution, and each of these movements represents several revolutions of the motor.

From the above it will be evident that the gear-wheel M⁶ constitutes a part moving with the semaphore-blade, and as this gear-wheel is within the signal-box it is a suitable part for engagement with the locking or engaging device which I will now describe.

The locking device comprises, as shown, a sliding locking piece or bolt or pin O, adapted to engage with the gear-wheel M⁶, and also comprises means for actuating said locking-pin O, and perforations m^7 m^8 m^9 are shown as formed in the web of the wheel M⁶, into any one of which perforations said locking-pin O will enter when the locking-pin is released or is in condition to engage with the wheel by entering a perforation thereof and the wheel M⁶ has moved to a position with a perforation in line with the pin. For the three signals "home danger," "distant danger," and "safety" there are six perforations

formed in the wheel M^6 , arranged in pairs diametrically opposite each other, for the reason above stated that the signal gives corresponding indications in diametrically opposite positions of the semaphore-shaft B^3 . As shown in Figs. 2, 3, and 4, the front end of the locking-pin O is within one of the two perforations m^7 , and thereby the signal is locked at the home danger position.

10 The means for moving the locking-pin O rearwardly, thereby withdrawing said pin from engagement with the wheel M^6 , consists of the electromagnet I , shown in the form of a horseshoe-electromagnet having two bobbins 15 or coils, one on each side of the locking-pin O , and the iron cores of said coils being joined at their rear ends by a suitable iron piece o^2 , which piece o^2 provides the rear bearing for the locking-pin O , and the cores terminating 20 at their front ends in long poles $o^3 o^3$, preferably covered by thin brass sleeves, and the perforated armature O' , fitting loosely over the sleeved poles of this electromagnet I , is secured to the locking-pin O , as by being 25 pinned thereto, as shown in Fig. 4, so that the locking-pin O moves with the armature O' , and when the electromagnet I is energized the armature is attracted and the locking-pin O withdrawn from engagement with the gear-30 wheel M^6 , and thus the signal is unlocked.

Continuously-acting means are employed tending to restore the locking-pin O to engaging position, such means, as shown, consisting of a coiled or helical spring O^4 , arranged 35 above the locking-pin O and secured at its forward end to the standard o^6 of the frame, which standard forms the front bearing of the locking-pin O , and secured at its rear end to a pin o^5 , passing through the locking-pin 40 O , near its rear end, and extending upwardly therefrom. The spring O^4 constantly pulls the locking-pin forward, and whenever the electromagnet I is deenergized this spring holds the locking-pin either with its front end 45 entered in one of the perforations m^7 , m^8 , or m^9 or with its front end against the gear-wheel M^6 , ready to enter the first perforation m^7 , m^8 , or m^9 which is brought in line with the locking-pin, and thus holding the locking-50 pin either in engagement with the wheel M^6 or in condition for engagement with the wheel M^6 , and thus locking the signal or being in condition to lock the signal.

The spring holding-pin o^5 , which passes 55 through the rear end of the locking-pin O , is shown as extending downwardly beneath the locking-pin O and entering a bearing in a switch-lever I' , suitably pivoted at I^2 , and by reason of this connection the switch-lever I' 60 moves with the locking-pin O , and thus the circuits made and broken by the switch-lever I' are controlled by the movement of the locking-pin O . It is to be noted that the mere putting of the locking-pin O into condition to 65 lock the semaphore will not affect the circuits controlled by the switch-lever I' , and these circuits will not be affected until the locking-

bolt moves forward into a perforation of the gear-wheel M^6 , and thus actually locks the signal.

70 The pivoted switch-lever I' is clearly shown in the diagrammatic views, Figs. 5 and 6. This lever is provided with a spring q at one end thereof and a spring i at the other end thereof, these springs being suitably insulated from the middle part of the switch-lever and from each other and working over contact-plates to make and break electric circuits in the manner hereinafter described.

75 It is to be noted that the switch-lever I' is shown in all views of the drawings in the position in which it is held when the locking-pin O is in engagement with the gear-wheel M^6 and the signal locked, and that when the locking-pin moves rearwardly out of the locking position the switch-lever is moved into 80 such position that the spring q is out of contact with the plate r and the spring i is out of contact with the plate o and in contact with the plate i^2 .

85 To make and break the necessary circuits to effect the automatic movements of the signal from one position to another, I employ a commutator in connection with the instrumentalities directly actuated by the train, 90 and this commutator is shown as of cylindrical form and secured upon the semaphore-shaft B^3 and contains upon its periphery a number of contact-plates insulated from each other, the configuration and arrangement of 95 these plates being best shown in the diagrammatic views, Figs. 5 and 6, in which views developments of the entire peripheries of two slightly-different commutators are shown, the commutator Q of Fig. 5 being of the construction employed for rail-circuit systems, and the commutator Q' of Fig. 6 being of the 100 construction employed for track-instrument systems.

105 Commutator-brushes are shown arranged to bear upon the commutators, those of the rail-circuit commutator Q being lettered h' $h^2 h^3 h^4 h^5 h^6 h^7 h^8 h^9$, respectively, and those of the track-instrument commutator Q' being lettered $q' q^2 q^3 p^4 q^5 q^6 q^7$, respectively. The 110 upper and lower boundary-lines x' of the developments of the commutators Q and Q' are the lines of contact of the commutators and brushes in the position shown—that is to say, with the signal locked in the home danger 115 position—and the middle dotted line x' in each commutator is the diametrically opposite line of contact, giving the same signal. The upper and lower dotted lines $x^2 x^2$ are the lines of contact for the distant danger-signal, and 120 the upper and lower dotted lines $x^3 x^3$ are the lines of contact for the safety-signal. The commutator Q is shown in Fig. 4 and in dotted lines in Fig. 3; but in Fig. 2 the semaphore-shaft B^3 is partly broken away and the commutator Q removed and the commutator-brushes also partly broken away. No 125 conducting-wires run from the commutator-plates, and in each construction the commu- 130

tator acts by making or breaking electric connection between different commutator-brushes.

I have shown the arrangement of circuits both for a system operated by the trains through rail-circuits and a system operated by the trains through track instruments, Fig. 5 showing the rail-circuit construction and arrangement, and Fig. 6 the track-instrument construction and arrangement, and I will first separately describe the rail-circuit system and will afterward describe the track-instrument system.

I have shown my improved signal in connection with the circuits of my improved railway signaling system shown, described, and claimed in my application for Letters Patent, Serial No. 546,637, filed April 22, 1895, modifying said circuits only so far as is necessary to adapt them to the improved signal embodying my present invention and to the realization in the construction and arrangement herein shown of all of the advantages of the invention of my said prior application, Serial No. 546,637.

The circuits and apparatus represented in Fig. 5 are those usually in proximity to one signal, in this instance the signal B', shown in the diagram alongside of the track and located near the rear end of and guarding the section of track marked B and being located near the advance end of the section of track marked A. The apparatus and commutator shown in Fig. 5 are those for actuating said signal B'. It will be readily understood that the track-section A will be guarded by a similar signal, which will be hereinafter referred to as signal A', and this signal will be provided with similar circuits and apparatus, and so also will be the next signal in advance of B', which will be hereinafter referred to as signal C', and the section of track guarded by signal C' will be hereinafter referred to as section C, and it is of course evident that any desired number of blocks or sections may be employed.

Assuming that the signal B' is in the home danger position—that is to say, the semaphore-blade B⁷ is in horizontal position and the lantern L shows a red light—and that a train enters upon the track-section A, the train will shunt the circuit of the track-electromagnet E (not shown) of section A, thereby closing at the contacts k l of said electromagnet E of section A the circuit of the electromagnet G (not shown) of section A, and thus closing the contacts w v of that electromagnet, and thereby closing the normally open circuit of the electromagnet H (shown) of section B, as the current will then flow from the battery X shown through wire 15, wire 3, rail a of track-section A, and then through the following parts of the circuits at signal A'—viz., wire 2, wire 17, commutator-brushes h⁶ and h⁷, wire 13, contacts q r, wire 18, contacts w v, wire 14, and through wire 14 to the circuits at signal B', as follows: wire 14, electromagnet H,

commutator-brushes h³ h⁴, wire 8, contacts h g, and wire 16 back to battery X. It is to be noted that if the signal A' is at rest in any other position than "home danger" the brushes h⁶ and h⁷ of that signal will not be electrically connected by the commutator of A'; also, that if the signal A' is in motion and changing from one position to another the contacts q and r of signal A' will be separated; also, that if the signal B' is already in the safety position or in the distant danger position the brushes h³ and h⁴ of signal B' will not be electrically connected by the commutator of B; also, that if there is a train in section B the contact of g and h is broken, and therefore, unless the signal A' is at rest in the home danger position and the signal B' returned to the normal danger position after the preceding train and the section B is clear of trains, the circuit above described energizing the electromagnet H will not be closed by the presence of train on section A. When, however, the conditions permit this circuit to be closed, the signal will thereby be started in its movement toward the safety position by the withdrawal of the lock-pin O and the closing of the motor-circuit, as the energization of the electromagnet H effects the closing of the contacts n p, which closes the circuit of the lock-actuating electromagnet I as follows: from battery X through wire 15, wire 3, wire 19, contacts n p, wire 9, electromagnet I, and wire 6 back to battery X, thereby effecting the withdrawal of the lock-pin O, and the withdrawal of the lock-pin moves the lever I', so as to bring the spring i upon the contact i², thereby closing the motor-circuit as follows: from battery X through wire 15, wire 3, motor M, wire 3, contacts i² i, and wire 6 to battery X. The current flowing through the motor actuates it and starts the movement of the signal in the direction of the arrows in Fig. 1 from the home danger position, thereby rotating the commutator also in the same direction, as indicated by the arrow in Fig. 5. As will be seen, a short movement of the commutator breaks the electric connection of the brushes h³ and h⁴, thereby cutting off the current from the battery X to the electromagnet H; but this movement of the commutator also puts the brush h³ into electric connection with the brush h⁴, thereby closing a circuit through the electromagnet H from the battery located at the next signal C' in advance of the signal B' shown, said circuit being as follows: from the battery X (not shown) at the signal C' through wires 15 and 3 thereof to rail b, and thence rearwardly to the circuits and instruments shown, through wire 2, wire 17, brush h⁶, brush h⁵, (these brushes h⁶ h⁵ being now connected by the commutator,) wire 14, magnet H, brush h³, brush h⁴, wire 10', and through wire 10' forward to circuits located at signal C', and through wire 8 thereof, contacts h g thereof, and wire 16 thereof back to battery. Now if the contacts h g of signal C' are closed, the electromagnet H shown will be energized

by this circuit and the lock-pin O held in withdrawn position, and therefore the signal will pass the distant danger position without being locked. This will happen if the section C, as well as the section B, is clear of trains; but if there is a train in C the magnet G of that section will be energized, and therefore the contacts $h\ g$, controlled by that magnet, will be open, and a break will therefore exist in the circuit above traced from the battery X of signal C', and no current will flow to the electromagnet H shown, and consequently the lock-actuating magnet I will be deenergized as soon as the electric connection of the brushes $h^3\ h^4$ is broken by the commutator, and therefore the lock-pin O will be released and put in condition to enter the next perforation that comes in its path—viz., the perforation m^8 —whereby the signal B' is locked with the semaphore B⁷ in oblique position and the lantern L showing a green light, thereby giving the distant danger signal. This indicates to the train-engineer that one section in advance is clear and the second section in advance is occupied by a train. If, however, the section C is clear of trains, then the energization of the lock-actuating magnet I will continue until the signal has passed the distant danger position; but between the distant danger and the safety positions the connection of the brushes h' and h^3 , through the commutator, will be broken, and thereby the circuit, above described, from battery X of signal C' will be broken and the lock will be released, and thus put in condition for engagement with the next perforation of the wheel M⁶ that comes in its path—viz., a perforation m^9 —whereby the signal B' is locked with the semaphore-arm B⁷ vertical and the lantern L showing a white light, thus giving the safety indication and with the arrangement shown indicating to the engineer that two blocks in advance are clear of trains. When the signal B' thus assumes a safety position, the track-circuit of the rear signal A' is broken between the brushes h^8 and h^9 of the signal B', said track-circuit normally running from the battery X, (shown,) through wires 15 and 3, to rail a, thence through the track-electromagnet E (not shown) of section A', thence returning by the other rail and through the wire 4 (including the resistance R) to brush h^8 , and from the brush h^9 , through wire 21, contacts o and i, and wire 6, to battery X. It will be seen that this circuit is broken between h^8 and h^9 when the signal B' is locked in the distant danger position or in the safety position and is broken between i and o when the signal is in motion, and is therefore only closed when B' is locked in the home danger position, and thus the electromagnet E of section A is prevented from breaking the contacts k and l, controlled by said electromagnet E, until the signal B' has returned to the home danger position, and the break at k l maintains the break at g h of the circuits at A', and thus effectually

locks the signal A' at the home danger position until the signal B' has returned to the home danger position behind the train. 70

When the signal B' assumes the safety position, the circuit of the electromagnet H (not shown) of the advance signal C' is broken between the brushes h^6 and h^7 of the signal B', and, as will be seen, this break will also 75 occur when the signal B' is in the distant danger position, and when the signal B' is unlocked this circuit will be broken between the contacts q and r of the signal B'. Thus the signal C' will be locked at the home danger position until the signal B' has returned to the home danger position behind the train. 80

Assuming now that the train, having received the safety indication from the signal B', passes onward from the track-section A 85 to the track-section B, the train will first shunt the track-electromagnet E shown, thereby closing the circuit of the electromagnet G shown, and thus closing at the contacts g m a circuit which will cause the signal B' to go 90 to the home danger position, said circuit being as follows: from the battery X shown through wires 15 and 3 and then through rail a to the rear end of said rail at signal A', then through the following conductors and contacts at signal A', viz: wire 2, wire 17, brushes h^6 and h^7 , wire 13, contacts r q, wire 18, contacts w v, wire 14, and forward through wire 14 and through the electromagnet H at signal B', brushes $h^3\ h^2$, wire 20, contacts m g, and wire 100 16 back to the battery X shown. The electromagnet H will then close at n p the actuating-circuit of the electromagnet I, above described, which will cause the withdrawal of the locking-pin O and the closing of the 105 motor-circuit and starting of the signal; but after the signal has moved a short distance the connection between the brushes $h^3\ h^2$ is broken by the commutator, and thus the circuits above described, except the motor-circuit, 110 are broken and the locking-pin is put into condition to enter the next perforation, which will be a perforation m^7 , and when the pin enters said perforation the signal B will be locked in the home danger position and 115 the motor-circuit broken. It is to be remembered that the actuating-circuit of the electromagnet E at signal A' is broken until the signal B' has returned to the home danger position, and therefore, even if every portion 120 of the train has at this time entered the track-section B, and consequently the shunting by the train of the electromagnet E at signal A' has entirely ceased, nevertheless the contacts v w at signal A' will remain closed while the signal B' is in the safety position and while the signal B' is moving from the safety to the home danger position and until the signal B' has been actually locked in the home danger position. 125 130

As the locking-pin O of the signal B' moves into engagement with a perforation m^7 , as aforesaid, thereby locking the signal B' in the home danger position, the contacts q and

r of signal B' will be closed, and as the brushes *h*⁶ and *h*⁷ of signal B' have been electrically connected by the commutator and the contacts *v w* at signal B' were closed by the entrance of the train upon the track-section B the circuit is now closed, which initiates the operations for putting the signal C' into the position required by the condition of the track, said circuit including the contacts *v w*, the contacts *q* and *r*, and the brushes *h*⁶ and *h*⁷, all at signal B', and the electromagnet H at the signal C', and the adjacent circuits will then operate as above described in relation to the signal B' to put the signal C' to safety or distant danger in accordance with the condition of the traffic on the tracks. After the train has passed out of the track-section B and into the track-section C its control over the signal B' will be continued to the extent that by maintaining a break at the contacts *h g* at signal C' it will prevent the signal B' when actuated by a train on track-section A from being moved beyond the distant danger position. After the train has passed out of section C it ceases to affect the signal B'.

I will now describe the track-instrument system illustrated in Fig. 6. The circuits and apparatus represented in this figure are those usually in proximity to one signal—in this instance the signal B', shown in the diagram alongside of the track, and the apparatus and commutator shown are those actuating said signal B'. This signal B' guards the section of track marked B and is located at the advance end of the section of track marked A. The next section in advance of B will be referred to as section C, and it will be understood that sections A and C will be provided with similar circuits and apparatus to those shown.

The trains will actuate the circuits and apparatus through the medium of track instruments. One of these track instruments T is shown in outline or diagram in proximity to the signal B', and it will be understood that a corresponding track instrument will be provided in proximity to each signal along the line.

Assuming that the signal B' is in the home danger position and that a train enters upon the track-section A and actuates the track instrument (not shown) at the rear end of said section, the circuits normally closed by this track instrument will be broken and the pair of electromagnets S and S' of the signal A', the signal in rear of signal B', will be de-energized. The normally-closed circuit of these electromagnets S and S' flows from the battery X at signal A' through wire 6, wire 25, electromagnet S, wire 26, electromagnet S', wire 26, the track instrument, and wire 3 back to battery. The de-energization of the electromagnets S S' closes the contacts *d* and *d'*, but it is necessary to also close the contacts *f f'* before the advance signal-actuating circuit is closed, and this is not effected until the track instrument is closed after oper-

ation by the train. When the track instrument thus closes, the circuit above described energizing the pair of electromagnets S and S' is again closed, but the armatures *d* and *e* are in lower position and will be maintained in such position. The closing of the track instrument also effects the closing of the circuit, which closes the normally open contacts *f f'*, said circuit including the following parts of the circuits at signal A' only, viz: from the battery through the wire 27, contacts *j j'*, wire 28, contacts *e e'*, key *x*, wire 36, commutator-brushes *q*² *q*¹, wire 37, electromagnet V, wire 38, wire 18, contacts *q r*, wire 13, track instrument, and wire 3 back to battery. The circuit for energizing the electromagnet H at signal B' is now completely closed, this circuit being as follows: from the battery X shown at signal B' through wire 27, contacts *j j'*, wire 28, contacts *e e'*, wire 29, commutator-brushes *q*⁵ *q*⁴, wire 30, electromagnet H, and then by wire 14 rearwardly through the following parts of the circuits at signal A', viz: wire 14, electromagnet W', wire 31, contacts *f' f*, wire 32, contacts *d d'*, and wire 33 to ground, and from the ground connection U shown at signal B' back to battery. The energization of the electromagnet H causes the signal B' to be started in its movement toward the safety position by the withdrawal of the lock-pin O and the closing of the motor-circuit, as the energization of the electromagnet H effects the closing of the contacts *n p*, which closes the circuit of the lock-actuating electromagnet I, as follows: from battery X, through wire 3, wire 19, contacts *n p*, wire 9, electromagnet I, and wire 6, back to battery, thereby effecting the withdrawal of the lock-pin O; and the withdrawal of the lock-pin moves the lever I', so as to bring the spring *i* upon the contact *i'*, thereby closing the motor-circuit as follows: from battery X, through wire 3, motor M, wire 3, contacts *i' i*, and wire 6, back to battery. The current flowing through the motor actuates it and starts the movement of the signal and rotates the commutator in the direction indicated by the arrow in Fig. 6, and a short movement of the commutator breaks the above-described circuit of the electromagnet H at the brushes *q*⁴ *q*⁵; but this movement of the commutator also closes a circuit through the electromagnet H from the battery located at the next signal C' in advance of the signal B' shown, said circuit being as follows: from the battery X (not shown) at the signal C', through wire 27, contacts *j j'*, wire 28, contacts *e e'*, wire 10', and thence rearward to the circuits and instruments shown through wire 10', commutator-brushes *q*³ *q*⁴, wire 30, electromagnet H, wire 14, and thence rearward by wire 14 to signal A' and through electromagnet W', wire 31, contacts *f' f*, wire 32, contacts *d d'*, wire 33, to ground at the ground connection (not shown) at signal A', and from the ground connection (not shown) at signal C' back to battery. Now if the contacts *e e'* of signal C' are

closed the electromagnet H shown will be energized by this circuit and the lock-pin O held in withdrawn position, and therefore the signal will pass the distant danger position without being locked. This will happen if the section C as well as the section B is clear of trains; but if there is a train in C contacts $e' e'$ thereof will be open and no current will flow to the electromagnet H, and the signal B' will be locked as soon as it reaches the distant danger position. If the section C is clear of trains, then the signal will be carried beyond the distant danger position, but between the distant danger and safety positions the contact between the commutator-brushes $q^3 q^4$ will be broken, and the lock therefore will be released and put in condition for locking the signal, and when the signal reaches the safety position it will therefore be locked. The movements above described may take place deliberately, as the circuits which initiate the movements of the signal remain in condition for initiating such movements during the entire time that the train is passing from the rear end of the section A to the advance end thereof or from track instrument to track instrument.

Assuming now that the train having received the "safety" indication from the signal B' passes that signal and operates the track instrument T shown, the normally-closed circuit of the pair of electromagnets S and S' shown will be broken and will close a circuit energizing the electromagnet H shown as follows: from the battery X shown through wire 27, contacts $j' j$, wire 28, contacts $e^2 e^3$, key x , wire 36, commutator-brushes $q^2 q^4$, (these brushes being now electrically connected, as the signal B' is in the safety position,) wire 30, electromagnet H, wire 14, wire 34, contacts $f^2 f$, wire 32, contacts $d d'$, and wire 33 back to battery. This initiates the movement of the signal B' from the safety to the home danger position, and before the signal reaches the home danger position the electrical connection of the commutator-brushes $q^2 q^4$ is broken by the movement of the commutator, and therefore the signal is locked when it reaches the home danger position. So long as the track instrument T is open the following circuit will be maintained, viz: from the battery (not shown) at signal A', through wire 6 thereof, contacts $i o$, controlled by switch-bar I', wire 55 21, commutator-brushes $q^7 q^6$, wire 35, electromagnet W, and through wire 14 to and through the following parts of the circuits at the signal B', viz: wire 34, contacts $f^2 f$, wire 32, contacts $d d'$, and wire 33 to ground at U 60 and from the ground connection at the signal A' back to battery. The armatures of the pair of electromagnets W W' at the signal A' are thereby raised and the contacts $i' i'$ are closed, completing the following circuit, viz: from the battery at signal A', by wire 6 thereof, wire 25, electromagnet S, wire 40, contacts $i' i$, wire 14, and forward to the signal B' and

through the following parts of the circuits thereof: wire 34, contacts $f^2 f$, wire 32, contacts $d d'$, wire 33 to ground at U and from the ground connection at the signal A' back to battery. This causes the armatures d and e of the pair of electromagnets S S' at the signal A' to be returned to their upper or normal positions and breaks at $j' j$ and $e' e^3$, the circuit above described energizing the electromagnet V at signal A'. With the signal B' at "danger" and the track instrument T closed the electromagnet V at signal B' is energized by the following circuit: from battery X shown through wire 3, track instrument T, wire 13, contacts $r q$, wire 18, wire 38, electromagnet V, wire 37, brushes $q' q^2$, wire 36, key x , contacts $e^2 e$, wire 28, contacts $j' j$, and wire 27 back to battery. Thus armature f of electromagnet V is raised, breaking at f^2 , the circuit above described energizing electromagnet W at A' and dropping the armatures i and j at signal A' to lower and normal position.

The track-instrument system shown in Fig. 6 in connection with the present invention will form the subject of a separate application for Letters Patent and has not therefore been fully described, except so far as is necessary to bring out the operation of the parts embodying the present invention in connection therewith. It is to be noted, however, that when a track instrument is closed after having been opened by a train and the circuit above described energizing the electromagnet V at the same signal has been thereby closed, a local circuit is closed, including the electromagnets V' and V and excluding the track instrument maintaining the armature f in upper position, notwithstanding backward and forward movement of the train such as would cause a repetition of the operation of the track instrument, and the armature of the electromagnets V and V' will not be disturbed thereby, and it is also to be noted that the armatures of the electromagnets S and S' will not be disturbed by such repetitions of the movement of the same track instrument, and therefore such repetitions of the movement of the same track instrument will not effect any change in the signaling-circuits.

Another feature of the track-instrument system shown is the means for setting the signals by hand in the event of disarrangement through failure of one signal to operate. This may be done by the key x shown. If a train in passing the next advance track instrument to that shown failed to set the signal C' to "danger" because the armatures d and e at signal C' failed to drop, there would be no circuit for raising the armatures of electromagnets S and S' at signal B' to their upper or normal position, and therefore the contacts $e' e^3$ at signal B' would remain closed and the armature f would remain in contact with point f' . A following train would have to pass signal B' at "danger," and $f f'$ at signal B' being closed there would be no circuit to re-

store the armatures d and e at signal A' to upper normal position; but before passing the track instrument T shown the engineer would open the key x , thereby deenergizing the coils of electromagnets V and V' and closing the contacts f and f' all at signal B'. Further, if the armatures d and e at signal C' dropped, but the signal failed to go to "danger," then the electromagnets W and S at signal B' would remain so energized as to hold up their armatures. The train above referred to would in passing signal B' clear signal A', but a following train could not clear A' by the use of the key x at B', as before described, because as the armatures d , e , i , and j , all at B', are held up there would be no circuit via line 14, owing to the break at d' . Consequently a third train would find signals A' and B' locked at "danger," and armature f at A' would be on f' ; but the engineer of the third train could by use of the key x at A' clear the signal to rear of A'. It is also to be noted that normally a circuit may be traced from the battery X shown, through electromagnet H shown, and also through electromagnet W at signal A'; but this circuit is inoperative, for the reason that it also includes the electromagnets S and S' of rear signal A', the resistance of the latter coils preventing serviceable energization of the electromagnet H shown.

It will be seen that the line 14 has two branches which are energized at different times in the operation of the system, but the electromagnet H can only be serviceably energized via lower electromagnet W' of the pair of electromagnets W W' and the electromagnet S (shunting S') can only be energized when the branch of line 14 including electromagnet H is cut off.

40 One source of trouble in automatic systems is the liability of running down or failure of the battery, and where a single battery is employed at each signal, as in the systems above particularly described, the failure of the battery at any signal will make that signal totally inoperative and will also seriously affect adjacent signals. Two different constructions of means embodying my invention for guarding against battery failures are separately shown in Figs. 7 and 8, each exactly as it would appear if connected in the circuits shown in Fig. 5; but these means are omitted from Fig. 5 to prevent confusion as to the other circuits shown in Fig. 5. In each construction X is the main or active battery and X' the reserve battery with the circuit-breakers closed, as shown; but the relations of these batteries are interchangeable and either one may be the main or active battery and the other one the reserve battery.

Two electromagnets D and D' are provided, each in a shunt-circuit including one of the batteries, the electromagnet D being in a shunt-circuit including the battery X and the other electromagnet D' in a shunt-circuit including the other battery X'. The wires 15 and 16 represent the correspondingly-numbered wires in Fig. 5, and it is to be understood that these wires are to be connected with the circuits shown in this figure to form a complete signaling system embodying my invention. It is also evident that these wires may be the terminals of an actuating-circuit.

Referring first to Fig. 7, the current flows from the battery X, through the wire 41 and contacts y^5 y^4 , to wire 16, and returning through wire 15 passes through branch 45 back to battery X. The shunt-circuit for the electromagnet D branches from the wire 41, through wire 47, electromagnet D, and wire 80 42 back to the main circuit at wire 15. It will be seen that this shunt-circuit is permanent, having no make-and-break device therein, and therefore the electromagnet D is always connected with the battery X. The battery X' is connected by the wire 43 with the contact-stop y^6 , but the armature y^4 , connected with the line 16, is in upper position, and therefore the circuit of the battery X' is broken between the armature y^4 and contact y^6 and remains broken so long as the armature y^4 is in upper position. The return-current of this circuit would pass from the wire 15 through branch 46 back to battery X'.

The shunt-circuit for the electromagnet D' passes through wire 48, electromagnet D', and wire 44 back to the main circuit at wire 15, and this shunt-circuit contains no make-and-break device and is therefore always closed. So long as the current flowing through the magnet D' is strong enough to hold the armature y^1 against the contact-stop y^5 the armature will be maintained against this stop y^5 , and the main circuit will be actuated by the battery X and the battery X' will be cut out; but if at any time the battery X ceases to supply electric current or the current supplied by said battery X diminishes, so as to be not sufficiently strong to hold the armature y^4 against the stop y^5 , the armature will drop upon the contact y^6 , and the battery X will thereby be cut out of the main circuit and the battery X' connected in that circuit. As will be seen, the electromagnets are arranged so as to tend to attract the armature in opposite directions; but when the armature is in close proximity to one of them it will remain there, notwithstanding the attraction of the other electromagnet, so long as the current supplied to the former electromagnet is maintained at predetermined strength.

In the construction shown in Fig. 8 the electromagnets D and D' act independently of each other, and each is provided with two armatures, one armature in the main circuit of its own battery and the other armature in the shunt-circuit of the other battery, and thus when the main circuit of a battery is closed the shunt-circuit of the other battery is broken. The parts are lettered and numbered to partially correspond with Fig. 7. The main current from battery X flows through wire 41, contact y^2 , and armature y to wire 16, and returning through wire 15 passes by

branch 45 back to battery X. The shunt-circuit branches from the main line through armature z' , contact z^8 , wire 49, electromagnet D, and wire 42 back to main line at wire 15, and therefore includes an armature and contact controlled by the electromagnet D' of the other battery X', so that when the electromagnet D' is energized this shunt-circuit is broken. The main current from the battery X', if the contacts were in opposite position, would flow through wire 43, contact y^3 , armature y' to line 16, and returning through line 15 would go back to battery through branch 46. The shunt-circuit branches through wire 51, armature z , contact z^2 , wire 52, electromagnet D', and wire 44 back to line 15, and thus includes an armature and contact controlled by the electromagnet D of the battery X. The operation of the parts shown in Fig. 8 is the same as described in relation to Fig. 7; but in the construction of Fig. 8 the reserve battery is completely cut out, while in the construction of Fig. 7 a small amount of current from the reserve battery continually flows through the electromagnet in closed circuit therewith. The construction shown in Fig. 8 is particularly claimed herein.

It will be observed that in each of the two constructions of Figs. 7 and 8 there are two battery-contacts, one connected to the main battery and one connected to the reserve battery, and there are also circuit-contacts which close separately with one or the other of these battery-contacts, so that when one battery is connected in the main or actuating circuit the other battery is disconnected therefrom.

In Fig. 7, as shown, with X as the main battery and X' as the reserve battery, the main-battery contact is y^5 and the reserve-battery contact is y^6 . The circuit-contact for y^5 is the upper face of the movable contact-piece y^4 and the circuit-contact for y^6 is the lower face of the same movable contact-piece y^4 , or, as it may be otherwise stated, the movable contact-piece y^4 may be the circuit-contact for either one or the other battery-contacts.

In Fig. 8, as shown, with X as the main battery and X' as the reserve battery, the main-battery contact is y^2 and the reserve-battery contact is y^3 . The circuit-contact for y^2 is the movable contact-piece y and the circuit-contact for y^3 is the movable contact-piece y' .

From the above description of the signal-operating mechanism it will be evident that after the train has caused the withdrawal of the locking-pin and the slightest movement of the disk or gear wheel M^6 has taken place the operation of the mechanism will not be interrupted by any interruption in the circuit controlled by the train. The signaling mechanism is then under the control of the commutator and is relieved of the control of the train and will continue its movement to completion altogether independently of the train. In fact, the circuit closed by the action of the train is soon broken by the action of the commutator, and the commutator then

remains in control of the signal mechanism until the desired signal is given. This operation results in an economy of battery-power and a certainty of operation and a more deliberate operation than could possibly be attained if the signal had to respond as quickly as the train operated the circuit. It will also be noted that the actuating-circuits would retain their condition for initiating the movement of the actuating mechanism during the entire period while the train is passing through the section or block if there were no responsive action of the signal and in actual operation retain this condition for initiating the movement of the actuating mechanism until the responsive action of the signal.

From the above description it will also be evident that the motor starting and stopping device (shown as a circuit make and break device and comprising the pivoted switch-lever I' and its spring i and contact-plate o) is controlled by the locking device and that in the operation of the signal the release of the locking device in any position of the signal or indicator does not effect the locking of the signal or indicator until a predetermined position of the signal or indicator has been reached.

The improved signal-actuating mechanism, above described, embodying my invention is incased within a signal-box having an exposed bearing only at the shaft to which the semaphore is attached and but one exposed bearing at this shaft, all other parts being thoroughly incased and protected from moisture. The shaft carrying the lantern, being a vertical shaft, may be capped, as shown, and thereby thoroughly protected; but a horizontal shaft cannot be thus protected, and it is therefore of great advantage to limit this exposure to a single bearing of a single shaft. This is an important feature of my invention, as it is well known that the signals frequently remain at rest for long periods of time and are liable to become rusted at the bearings, so as to be inoperative; but with my improved signal the effect of the weather is minimized and does not, in fact, materially interfere with the operation of the mechanism. It will also be noted that there is no tendency to movement of the signal and no pressure upon the forward end of the lock-pin when the lock-pin is being withdrawn to unlock the signal, and therefore that during the unlocking movement there is practically no friction between the disk or wheel M^6 and the lock-pin; but after the lock-pin has been withdrawn the motor-circuit is closed and the motor moves the signal. This is an important feature of my invention and overcomes a great objection to all counterweight or gravity signal-actuating mechanisms, as in such mechanisms the locking device has to overcome a considerable amount of friction in unlocking the signal. It is to be noted, however, that my broad invention is not limited to the employment of an electromotor, nor to a circuit make and

break device for starting and stopping the motor, nor to an electromagnetic locking device.

It is of course evident that my improved signal mechanism is applicable to manually-operated systems or lock-and-block systems, and although automatic systems operated directly by the train have been shown and described my broad invention is not limited to such systems.

What I claim, and desire to secure by Letters Patent, is—

1. A signal for railways comprising a post or support, an arm extending therefrom, a substantially straight semaphore-blade broader than the arm and fitted to rotate in a plane substantially vertical and substantially at right angles to the direction of traffic, and pivoted to the arm at such a distance from said post or support as to be substantially clear of the background of said post or support in all positions of a full revolution, and means for rotating said semaphore-blade and for stopping and holding at rest said semaphore-blade in one or more predetermined positions, substantially as set forth.

2. A block-signal for railways comprising a post or support, an arm extending therefrom, a substantially straight semaphore-blade broader than the arm and fitted to rotate in a plane substantially vertical and substantially at right angles to the direction of traffic, and pivoted to the arm at such a distance from said post or support as to be substantially clear of the background of said post or support in all positions of a full revolution, and means for rotating said semaphore-blade when changing from one position to another and for stopping and holding at rest said semaphore-blade in one position to indicate that a plurality of blocks in advance is clear and in a second position to indicate that the block in advance is clear and in a third position to indicate that the block in advance is occupied, substantially as set forth.

3. A signal for railways comprising a supporting-post, a semaphore fitted to rotate in a substantially vertical plane, and pivoted at such a distance from said post as to be substantially clear of the background of said post in all positions of a full revolution, a lantern fitted to rotate on a substantially vertical axis, said semaphore and lantern being connected so as to rotate together and give corresponding indications and said semaphore being located on the same side of said post as said lantern, and means for rotating said semaphore and lantern and for holding said semaphore and lantern at rest in one or more predetermined positions, substantially as set forth.

4. A signal for railways comprising a supporting-post, an arm extending therefrom, a semaphore-blade broader than the arm and fitted to rotate in a plane substantially vertical and substantially at right angles to the direction of traffic, and pivoted to the arm at

such a distance from said post as to be substantially clear of the background of said post in all positions of a full revolution, and means for rotating said semaphore-blade and for stopping and holding at rest said semaphore-blade in one or more predetermined positions, and a lantern on the same side of the post as the semaphore-blade and arranged to give corresponding indications, substantially as set forth.

5. A signal for railways comprising a visual indicator giving signals by different positions thereof, a motor for the indicator, a locking device, a part at all times connected to and moving with the indicator, constructed to be engaged by the locking device in positions corresponding with the different positions of the indicator, and a commutator controlling the locking device so as to lock the indicator in predetermined positions to indicate the condition of the track, substantially as set forth.

6. A signal for railways comprising a visual indicator, an electromotor for said indicator, a locking device for the indicator having a locking-piece whereby the indicator is held at rest in one or more predetermined positions, and a circuit make and break combined motor starting and stopping device actuated by said locking-piece, the circuit of said motor having a single break therein controlled by said make-and-break device, substantially as set forth.

7. A signal for railways comprising a rotating visual indicator, a motor for rotating said indicator always in the same direction, a part moving with said indicator, a movable locking-piece engaging with said part to stop and lock the indicator in one or more predetermined positions of the indicator, a motor starting and stopping device controlled by the movement of said locking-piece so that the withdrawal of said locking-piece starts the motor and the engagement of said locking-piece stops the motor, and means for withdrawing the locking-piece and for putting the locking-piece in condition for engagement with said part moving with the indicator, substantially as set forth.

8. A signal for railways comprising a rotating visual indicator, a motor for rotating said indicator, a part moving with said indicator, a movable locking-piece engaging with said part to stop and lock the indicator in one or more predetermined positions of the indicator, an electromagnet for withdrawing said locking-piece, continuously-acting means tending to restore said locking-piece to engaging position, and a circuit make and break combined motor starting and stopping device actuated by said locking-piece and controlling the motor-actuating circuit, said motor-actuating circuit having a single break therein, substantially as set forth.

9. A signal for railways comprising a visual indicator and a motor and locking device for the indicator, a motor starting and stopping

device, and a commutator controlling the locking device and motor starting and stopping device so as to stop and lock the indicator in one or more predetermined positions 5 to indicate the condition of the track, substantially as set forth.

10. A signal for railways comprising a visual indicator and a motor and locking device for the indicator, a motor starting and stopping device controlled by the movement of said locking device, and a commutator controlling the locking device so as to lock the indicator in one or more predetermined positions to indicate the condition of the track, 15 substantially as set forth.

11. A block-signal for railways comprising a visual indicator adapted to assume three positions, indicating respectively "safety," "distant danger" and "home danger," said 20 indicator being normally in the home danger position, a commutator connected at all times to the indicator, a circuit controlled at the track-section in rear of the indicator and adapted to be also controlled at the section 25 guarded by the indicator for starting the movement of the indicator from the home danger position, and another circuit thrown into action by the movement of the indicator and commutator and adapted to be controlled a plurality of sections in advance, to 30 carry said indicator past the distant danger position, and a circuit for continuing the motion of the indicator after it has been started from home danger to distant danger, independently of the first-named circuit, and for 35 continuing the movement of the same from distant danger to safety after it has been carried beyond the distant danger position, independently of the last-named circuit, substantially as set forth.

12. In a block-signal for railways, in combination, an indicator and a commutator, means for actuating the indicator and commutator, and a locking device for the indicator controlled by a train to unlock the indicator, said actuating mechanism being relieved from the control of said train by the unlocking of the locking device and the initial movement of the indicator, and controlled 45 by the commutator through circuits not under the control of said train to complete the movement of the indicator, substantially as set forth.

13. In a block-signal for railways, in combination, an indicator and a commutator connected to move together, a motor and locking device for the indicator and commutator, means under the control of a train for unlocking said locking device and starting the 50 motor, and means under the control of the commutator independently of said train for controlling the motor and locking device to complete the movement of the indicator, substantially as set forth.

14. A signal for railways comprising an indicator and a commutator, means for moving and locking the indicator whereby said indi-

cator may be moved into and locked in one or more predetermined positions, and a circuit make and break device controlling the 70 moving and locking means to unlock and start the indicator, said circuit make and break device being relieved from the control of the indicator by the unlocking and initial movement of the indicator, and said indicator being controlled by the commutator through 75 circuits not under the control of said circuit make and break device to complete the movement of the indicator, substantially as set forth. 80

15. A signal for railways comprising a movable visual indicator free from tendency to movement while at rest, a circuit make and break device, an engaging device actuated by said circuit make and break device, whereby 85 the signal is held in one or more predetermined positions, a motor for said indicator in a circuit controlled by said engaging device, whereby the movement of said engaging device actuates the motor to move the indicator, and a commutator connected to the indicator whereby the circuit of the engaging device is controlled while the indicator is passing its one or more indicating positions, the motor-actuating circuit being controlled by 90 the engaging device while the signal is moving through all positions intermediate of its position or positions of indication, substantially as set forth.

16. A signal for railways comprising a visual indicator and means for moving the same, a single locking-piece for the indicator adapted to lock the indicator in different positions thereof to give different indications as to the condition of the track, and a commutator connected to and moving with the indicator and controlling the locking-piece, substantially as 100 set forth.

17. A signal for railways comprising a movable visual indicator free from tendency to 110 movement while at rest, a motor for the indicator, a movable locking device for the indicator, and a motor starting and stopping device controlled by the locking device to energize the motor after the indicator has been 115 unlocked and to deenergize the motor when the indicator is locked, substantially as set forth.

18. In combination, an actuating electric circuit, two batteries, electromagnets in circuit with each battery, battery-contacts connected with each battery, and circuit-contacts for each battery, a contact for each battery being controlled by an electromagnet of the other battery, whereby either battery may be 120 actively connected in the circuit until the current supplied falls below a predetermined point and will thereupon connect the other battery actively in said circuit, substantially as set forth. 125

19. In combination, an actuating electric circuit, two batteries, an electromagnet connected in a shunt-circuit with one of said batteries and another electromagnet connected

in a shunt-circuit with the other of said batteries, and contacts controlled by said electromagnets, the contacts of each battery controlled by the electromagnet of the other battery, whereby either one of said batteries is maintained in the actuating-circuit until the current supplied by said battery falls below a predetermined point and then is cut out and the other battery connected in the actuating-circuit, substantially as set forth.

15. In combination, an actuating electric circuit, two batteries, an electromagnet connected in a shunt-circuit with one of said batteries and a make-and-break device in said shunt-circuit, an electromagnet connected in a shunt-circuit with the other of said batteries and a make-and-break device in the latter shunt-circuit, the make-and-break device in each shunt-circuit being controlled

by the electromagnet in the other shunt-circuit, and other circuit make and break devices controlled by said electromagnets, whereby one of said batteries is maintained in the actuating-circuit until the current supplied by said battery falls below a predetermined point and then said battery is cut out and the other battery connected in the circuit, and the electromagnet in the circuit with the active battery breaks the shunt-circuit of the electromagnet of the cut-out battery, substantially as set forth.

This specification signed and witnessed this 2d day of December, 1895.

HENRY BEZER.

In presence of—

HERBERT H. GIBBS,

HENRY D. WILLIAMS.
